(57) **CLAIM**

The ornamental design for a faucet, as shown and described.

DESCRIPTION

FIG. 1 is a side elevational view of a faucet showing our new design;

FIG. 2 is a front elevational view;

FIG. 3 is a top plan view;

FIG. 4 is a rear elevational view;

FIG. 5 is a bottom plan view; and,

FIG. 6 is a perspective view.

The broken lines in the FIG. 4 are for illustrative purposes only and form no part of the claimed design.
